SHUTTLE

Emil E. Fuller, Woonsocket, R. I., assignor to
 Shambow Shuttle Company, Woonsocket, R. I.,
 a corporation of Rhode Island

Application December 12, 1931, Serial No. 530,611

3 Claims. (Cl. 139—215)

The present invention relates to shuttles and thread blocks therefor.

A common form of shuttle, used particularly for silk weaving, employs an arm having a plurality of thread eyes, in combination with a series of pins, the thread being bent in passing alternately through the eyes and over the pins. This type of tension device operates well but is open to the objection that it requires hand threading, which renders it unsuitable for coarser work.

The object of the present invention is to provide a tension device which operates by bending the thread in the path of feed and which may be employed in weft replenishing shuttles, and to this end, the invention comprises the shuttle and thread block hereinafter described and particularly defined in the claims.

In the accompanying drawing, Fig. 1 is a plan view of the preferred form of shuttle; Fig. 2 is an elevation of the front side thereof; Figs. 3 and 4 are bottom plan and rear side views of the thread block; Fig. 5 is a section on line 5—5 of Fig. 4; Fig. 6 is a top plan view of the tension device; Fig. 7 is a section on line 7—7 of Fig. 6; Fig. 8 is a plan view of a modified form of tension device; Fig. 9 is a section on line 9—9 of Fig. 8; Fig. 10 is an elevation of a modified form of tension device; and Fig. 11 is an end sectional elevation, on an enlarged scale, of the device shown in Fig. 10.

The illustrated embodiment of the invention comprises a shuttle 12, having a table 13, an eye 14, and a thread block recess in which is received a thread block indicated generally at 16. The thread block has a longitudinal thread passage 18 and is provided at the front end with a beak 23.

Beside the thread passage is a tension device which is shown in detail in Figs. 6 and 7, and which is received in a recess under the table 13 of the block. The tension device comprises a series of thread engaging plates, illustrated as three plates 22, 24 and 26, separated by two spacer plates 28 and 30, all of the plates being secured together by pins 32 at the bottom of the device and by a pin 34 which serves as a pivot for the tension lever 36. Each of the spacer plates is disposed at the lower left corner of the tension device to provide open vertical spaces 33 and 40 between the thread engaging plates and also to leave a rear space 42 to receive the tension mechanism. The bottom edge of each thread engaging plate is recessed to form horizontal thread feeding surfaces 44, and thread retaining shoulders 46 in front of the shuttle eye.

As indicated in Figs. 6 and 7, the end faces of the thread engaging plates are inclined downwardly away from the beak to lead the thread into the eye. These plates are of the same general form except for variations in length. Thus, the innermost plate 22 is longest and has a front face of least inclination, while the outermost plate 26 is shortest and has the steepest face. Accordingly, the face of the tension member, as a whole, is inclined both longitudinally and transversely to guide the thread into the recesses 44. These recesses 44, as well as the shoulders 46, are all in alignment.

Preferably, the bottom edges of the plates are rounded, as indicated in Figs. 3 and 5, to facilitate smooth passage of the thread without wear.

The tension lever 36 comprises a single piece of wire formed with parallel arms 48 lying in the spaces 33 and 40. The arms are connected at the front end and form a loop 50 which lies beside and below the beak. The rear ends of the wire are bent around the pivot 34 and one end is extended upwardly to form a loop 52. Tension is placed on the lever by an elastic piece 54, one end of which is connected to the loop 52, and the other end is passed through a hole in a screw 56 and knotted thereto. The screw is threaded into the base of the tension device and the head of the screw is received in an opening in the table 13. By turning the screw, an operation which may be carried out without removal of the block from the shuttle, the tension may be regulated.

A modified tension applying mechanism is shown in Figs. 8 and 9. The tension is applied by a coiled spring 58 surrounding a rod 60 which is held at one end in a post 62 by a set screw 64. The tension lever is constructed as in the first modification, the looped rear end being elongated to permit the necessary pivotal movement. The rod passes through the loop, and the spring takes between a stop 66 at the free end of the rod and a washer 70 which abuts the loop. The tension may be adjusted by loosening the set screw and sliding the rod through the opening in the post.

A modified, and in some respects preferable, form of tension device is shown in Fig. 10. In this construction, the thread feeding and guiding surfaces are formed by wires 75 which are bent to form bottom thread feeding surfaces 77 and inclined guiding surfaces 79 corresponding to the bottom and front surfaces of the plates of the first modification. The wires are also bent to form front thread retaining shoulders 80. Each

wire is bent at the rear end, as indicated at 82, to be received in a small positioning hole in the bottom plate of a U-shaped sheet metal frame 84. The wires are clamped in place by a block 83 secured to the plate by a screw 88, the block having longitudinal positioning grooves in which the wires are received. In the sides 88 of the frame is pivoted a small block 92, carrying the tension lever 94 which is of the same looped form as the lever 36. The rear ends of the loop are attached to the pivoted block by a screw 96. A tension applying mechanism, illustrated as an adjustable elastic piece, is connected between the pivoted block and an adjusting screw 98. This construction may be preferred because of its cheapness and its light weight.

In operation, on the first pick of the shuttle after replenishment, which is represented by a movement of the shuttle from right to left, the thread is received in the thread passage and is caught by the beak in the usual manner. On the next pick, the thread is first drawn under the beak and over the tension lever, as indicated at 72 in Fig. 2. As the shuttle proceeds from left to right, the thread passes down the sloping face 74 of the shuttle into the eye, being drawn over the inclined front guide faces of the thread engaging plates and at the same time, depressing the tension lever. The thread finally feeds under the lower feeding surfaces 44 of the plates, engaging with all of them simultaneously, and over the arms of the tension lever, as shown in dot-and-dash lines in Figs. 1 and 5.

It will be seen that the present invention provides for placing a delicate, yet positive and uniform tension on the thread, regardless of any variations in feed from the bobbin. The device operates by bending or deflecting the thread in

the path of travel, as distinguished from friction devices, and is therefore very durable. The device also acts automatically to take up any slack in the thread, which usually occurs as the motion of the shuttle is resisted in being engaged by the shuttle box at the end of each flight. The device may be used with a shuttle of any type, but is particularly useful with automatic or weft replenishing shuttles because it in no way interferes with the replenishing operation.

Having thus described the invention, what is claimed is:

1. A shuttle having an eye, a block, a plurality of wires extending from the block and having spaced horizontal bottom feeding surfaces and inclined front guiding surfaces at different inclinations, the surface nearest the eye having the greatest inclination, and a loop tension lever having arms movable between the wires.

2. A shuttle having an eye, a block, a plurality of wires extending from the block, each wire being bent to form a horizontal bottom feeding surface, a retaining shoulder and an inclined guiding surface, the guiding surfaces being at different inclinations, the surface nearest the eye having the greatest inclination, and a tension lever having arms movable between the wires.

3. A tension device for shuttles comprising a U-shaped sheet metal frame, a plurality of guide wires extending forwardly from the frame and having their front ends inclined upwardly, a clamping block attached within the frame and having grooves within which the wires are clamped and positioned, a pivoted block in the frame, and a wire tension lever carried by the block and having arms extending between the guide wires.
